PRESSURE DEVICE

William H. Nutt, Beverly, Mass., assignor to
 United Shoe Machinery Corporation, Paterson,
 N. J., a corporation of New Jersey

Application March 23, 1935, Serial No. 12,648

26 Claims. (Cl. 12—51)

This invention relates to devices by which pressure may be applied to portions of shoes to perfect their form between other steps in their manufacture, it being particularly adapted for operation on shoe-shanks.

In the production of shoes, of which those of the turn-type furnish an example, it may be desirable, as a preliminary to relasting or other operations, to force the shank-portion of a shoe 10 into intimate contact with the last which it contains, this, at the same time, urging the edge of the upper-material toward the position in which it is to be temporarily secured to the last. My invention has as an object the effective application 15 of such pressure by a relatively inexpensive device, convenient for use by the operator. For the attainment of this object, I furnish, in novel combination, a carrier, which may be a yoke-like member, having movable upon it pressure means, 20 as a slide, provided with a shoe-bottom-engaging member normally spaced from the bottom of a shoe supported upon the carrier and actuated by a lever having its fulcrum mounted upon said carrier. This lever, when moved by the operator, 25 will press the engaging member against the shoe-bottom. In this position, the slide, or other pressure means, is temporarily retained to exert continued pressure upon the work, which causes the material to which the pressure is applied to 30 conform to the last, and the upper to be correspondingly urged along the sides of the last. The pressure-portion of the slide is preferably of yieldable material in layers, the outer layer being less yieldable than an inner, so its work-contacting 35 surface will readily assume the contour of the opposed surface of the last; and the carrier is shown as having means to permit the work to be presented in different positions to facilitate its mounting and the application of pressure to it. 40 The pressure upon the shoe-bottom may be resisted not only by the engagement of the last with the carrier, but also by such a member as a flexible strap extending from said carrier in a loop about the toe of the shoe. Two embodiments of the invention are disclosed herein, and, in these, the mounting of the slide upon the carrier, the connections for the actuating lever, the pressure-retaining means and the work-positioning means assume different forms.

In the accompanying drawings are illustrated the two organizations referred to above. In these drawings,

Fig. 1 shows, in broken, side elevation, one embodiment of my improved device;

Fig. 2 is a vertical, sectional detail on the line II—II of Fig. 1, and

Fig. 3 is a view similar to Fig. 1 of another arrangement.

Referring to Figs. 1 and 2, we have a yoke-like carrier member 10 provided with two arms, one of which, designated by the numeral 12, is short and diverges from a second longer arm 14. The latter is curved upwardly over the companion arm. From the juncture of the two arms depends a spindle 16, which may be received by a socket in a bench, a portion of which is indicated at 18. This pivoted mounting allows the device to be turned to different angular positions about a vertical axis to present it and the work operated upon conveniently for the operator. The upper extremity 20 of the arm 12 may be curved convexly and at or near its center is an outward projection 22 which is preferably short and rounded. This projection is adapted to enter the spindle-hole of a last, as appears at s, this last having upon it a shoe S which is to be operated upon. As will later be made clear, this engagement between the yoke-arm, its projection and the last permits the latter to rock so it may better accommodate itself and the work to the pressure which is to be applied.

The arm 14 of the yoke has an extension in the form of a guide member 24, which, though it is pivoted to the yoke-arm upon a pin 26, is essentially a portion of the carrier. A vertical adjustment of the pin 26, and therefore of the extension 24, may be made by placing said pin in either of two openings 27, 27 in the yoke-arm 14. The purpose of this adjustment will be hereinafter stated. The guide member is slotted longitudinally to receive a slide 28, upon the lower end of which is pivoted at 30 a holder 32. This holder has opposite ways 34 at its under side, in which ways may be inserted a pressure-pad P of yieldable material, preferably made up of a plurality of sections of different densities. Rubber is suitable for the entire pad, all the sections being vulcanized together. At 36, we have a layer of relatively dense, hard rubber which has angular projections at its edges entering the ways 34; a second layer 38 may be of quite compressible sponge-rubber; while a layer 40 is of a density between those of the other two, it being firm but flexible. The yield of the layer 38 allows the pad to conform readily to the contour of the shoe-bottom and last, the layer 40 not materially resisting this, yet providing a comparatively durable contact-surface.

To cause movement of the slide 28 with its pres-

55

sure member, the upper extremity of said slide is engaged by the cam-end 42 of a lever L, having an arm 44 extending outwardly over the yoke-arm 14, where it may be grasped readily by the operator. The lever is fulcrumed between the spaced walls 46, 46 rising from the extension 24, a fulcrum-pin 48 extending between the walls. This pin may be inserted in either of two pairs of alined openings 50, 50, and may be received 5 in either of two depressions 52, 52 in the cam-portion 42 of the lever. This mounting serves to so adjust the relation of the cam-end of the lever to the slide that the effective length of said slide may be varied and the pad P caused 10 to have the desired extent of pressure-movement. A leaf-spring 54, attached at one extremity to the lever and extending along the depressions, guards against accidental displacement of said 15 lever from its fulcrum, yet, upon sufficient pressure by the operator, permits the shifting of either depression into co-operation with the pin 48. It will be observed that the cam-portion 42 has a flat end 56 and this may merge by curved faces 58 into the opposite parallel side-walls of the 20 portion 42. The curvature at 58 may be about a center which is midway between the two pin-positions in the openings 50. When the lever-arm 44 is raised to free the slide from the cam, the pad P is elevated to an inactive position by 25 expansion-springs 60, 60, seated in recesses in the extension 24, and engaging the under face of a plate 61 secured to the top of the slide. Upon depression of the lever-arm 44 from a normally 30 lifted position, the outer curved face 58 cams 35 the slide smoothly down to urge the pad against the shoe-bottom, engagement of the face 56 retaining the elements in their pressure-relation.

There should, of course, be means for resisting movement of the toe-portion of the shoe S and 40 last s away from the slide 28 and pad P while pressure is applied to the work. For this purpose, I have shown a strap 62 hung by links 63, 63 upon a pin 64 extending across the outer extremity of the extension 24. This strap, which may be of 45 spring-metal, has a loop 66 covered with leather or other protective material 68, and through which the toe of the shoe being operated upon may be passed as it is applied to the yoke-projection 22, it being thus retained against downward displacement. The vertical position of the loop may be varied by applying the pin 64 to either of two openings 70, 70 in the links 63. The 50 just-described adjustment of the strap and that of the yoke-extension 24 by application of the pin 26 to the chosen one of the holes 27, locates these elements to best position the work for the 55 operation upon it.

It will be assumed that the shank of a shoe is 60 to be formed by this device, and that the adjustments at 27 and 70, and either or both those at 50 and 52, have been made to properly hold the work for the operation and the elements of the device for the application of the desired degree of pressure. The lever-arm 44 is initially 65 thrown up, withdrawing the cam-surface 56 of the lever from contact with the slide-plate 61, thus allowing the springs 60 to raise the slide and its pressure-pad P. The operator, with the device turned in the socket of the bench 18 to a convenient angle about the axis of the spindle 16, slips the toe of a lasted shoe S through the loop 66 and settles the end of the last-cone upon the end of the yoke-arm 12, the arm-projection 22 entering the spindle-hole in the last. The lever-arm 44 may now be lowered, the spindle 16 turn-

ing in the bench-socket to adapt the device to the movements of the operator. The outer surface 58 of the lever cams down the slide, and the layer 40 of the pad is forced against the shoe-shank, the holder tilting about its pivot 30. The 5 pad, under the influence of the applied pressure, exactly conforms to the shank over the entire contact-surface and exerts a uniform pressure thereon. At this time, the last may rock upon the yoke-surface 28 to permit the work to adapt 10 itself in position to the direction of applied pressure. The work may be left upon the device for the time necessary to obtain the desired forming effect. Then the lever-arm 44 is raised to free the slide; the springs 60 elevate the pad P from the work; and the operator removes the shoe and its last for the performance of the various relasting operations.

In Fig. 3 of the drawings is illustrated another form of my improved pressure device. The organizations are very similar, the present arrangement differing chiefly in the means for positioning the work and for applying and retaining pressure. The yoke-arm 14 of the carrier 10 has an extension 70 secured rigidly to it, and between this extension and the adjacent end of the arm a slide 72 is guided for vertical movement and carries the previously described pressure-pad P. An actuating lever l is pivoted to the slide at 74 and, at its forward extremity, has a floating fulcrum furnished by a pin 76 passing through the upper end of a link 78. The lower end of the link is pivotally joined at 80 to a lever 82, fulcrumed at 84 between opposite spaced walls 86 of the extension 70. A second lever 88 is fulcrumed at 90 between the walls 86. At 92 the adjacent ends of the levers 82 and 88 have toothed engagement to move together. In the lower portion of the extension is a recess 94, one wall of which is furnished by the forward vertical edge of the 40 slide 72, while the opposite wall 96 upon the extension is inclined inwardly and upwardly. In the recess, forced upwardly by a spring 98 abutting against a plate 100 closing the bottom of said recess, is a retaining member in the form of a 45 clutch-ball 102. The upper portion of the ball projects between the walls 86, 86 below the free end of the lever 88.

The elements are shown in operating relation in the drawings, a lasted shoe S being put under 50 pressure by the lowering by the operator of an arm 104 of the lever l. When the operator releases his grasp upon the lever, the pressure is held by the ball 102, which the spring 98 wedges between the slide 72 and the inclined wall 96. 55 The inner extremity of the lever 82 is lowered by the pull which the lever l and link 78 have put upon the connection 80. Consequently, the opposite end of the lever 88 is raised above the ball 102. When the pressure-period has passed and 60 the operator wishes to free the work, he raises the arm 104. The pivot-pin 74 first serves as a fulcrum and the link 78 is lowered. This turns the lever 82 anti-clockwise, as viewed in Fig. 3, 65 swinging the lever 88 in the opposite direction. Said lever 88 contacts at its outer end with the ball 102, forcing it down against the spring 98. The retaining effect of the ball upon the slide 72 ceases, and continued elevation of the lever-arm 104, with the connection 76 as a fulcrum, elevates the pressure-pad P to its inactive position, 70 preparing the device for the removal of the shoe which has been operated upon, and the application of another upon the carrier. To limit the upward travel of the connection 80 when the 75

lever-arm 104 is depressed, the outer end of the lever 82 may engage the under side of a plate 106 secured to one of the walls 86. When the lever-arm 104 is lifted to free the work, a surface 108 upon the extension 78 provides a similar stop for the lever 82.

In this modification, there is no necessity for the introduction of pressure-adjustments, and the work-positioning adjustments may be simplified.

10 I have shown a last-spindle 110 of the usual length pivotally mounted at 112 upon a carrier-slide 114, this slide being movable in ways upon a short, horizontal arm 116 of the yoke 10. The capacity for horizontal reciprocation of the slide 15 114 and the oscillation of the spindle 110, combined with the pivotal movement of the pad-holder 32 about its pin 30, as previously described, permits the shank of the shoe S to be correctly located to receive the pressure of the 20 pad P.

Having described my invention, what I claim as new and desire to secure by Letters Patent of the United States is:

1. In a shoe-pressing device, a carrier arranged to support a lasted shoe, a slide movable upon the carrier and provided with a shoe-engaging portion, an actuating lever having a fulcrum mounted upon the carrier and movable by the operator to press the engaging portion of the 30 slide against the shoe, and a flexible strap extending from the carrier and forming a loop through which the toe of the lasted shoe may be thrust.

2. In a shoe-pressing device, a carrier arranged to support a lasted shoe, a pressure member movable upon the carrier and provided with a shoe-engaging portion, and an actuating lever having a fulcrum mounted upon the carrier and movable by the operator to press the engaging portion of the pressure member against the shoe, the carrier having means permitting the shoe to rock into different positions to accommodate it- 40 self to the applied pressure.

3. In a shoe-pressing device, a carrier arranged to support a lasted shoe, a slide movable upon the carrier and provided with a shoe-engaging portion, an actuating lever having a fulcrum mounted upon the carrier and movable by the operator to press the engaging portion of the 50 slide against the shoe, and a pivotal mounting for the carrier whereby the work and the carrier may be presented in different positions for the operation.

4. In a shoe-pressing device, a yoke having two arms extending opposite each other, a slide provided with a shoe-engaging portion and an actuating lever for said slide mounted upon the same arm of the yoke, and a last-engaging projection upon the other arm of said yoke.

5. In a shoe-pressing device, a yoke having two arms extending opposite each other, a flexible toe-engaging strap, a slide provided with a shoe-engaging portion and an actuating lever for said slide all mounted together upon the same arm of the yoke, and a last-engaging projection upon the other arm of said yoke.

6. In a shoe-pressing device, a yoke, a spindle projecting from the yoke for rotation in a bench, a slide provided with a shoe-engaging portion and an actuating lever for said slide mounted upon one arm of the yoke, and a last-engaging projection upon the other arm of said yoke.

7. In a shoe-pressing device, a carrier arranged to support a lasted shoe, an extension pivoted upon the carrier, a shank-pressing member

mounted to reciprocate in the extension, and means movable by the operator to urge the pressing member toward the shank.

8. In a shoe-pressing device, a carrier arranged to support a lasted shoe, an extension pivoted upon the carrier, a shank-pressing member mounted to reciprocate in the extension, means movable by the operator to urge the pressing member toward the shank, and a spring interposed between the extension and the pressing member to retract said pressing member.

9. In a shoe-pressing device, a yoke, a slide provided with a shoe-engaging portion and an actuating lever for said slide mounted upon one arm of the yoke, and a last-engaging projection upon the other arm of said yoke, such projection being formed to permit the last to rock upon the arm, said arm having a curved surface adjacent to the projection to facilitate the rocking of the last.

10. In a shoe-pressing device, a carrier arranged to support a lasted shoe, a slide movable upon the carrier and provided with a shoe-engaging portion, an actuating lever having a fulcrum mounted upon the carrier and movable by the operator to press the engaging portion of the slide against the shoe, and means arranged to permit the effective length of the slide to be changed.

11. In a shoe-pressing device, a carrier arranged to support a lasted shoe, a slide movable upon the carrier and provided with a shoe-engaging portion, an actuating lever having a fulcrum mounted upon the carrier and movable by the operator to press the engaging portion of the slide against the shoe, and means arranged to permit the fulcrum-point of the lever to be changed.

12. In a shoe-pressing device, a carrier arranged to support a lasted shoe and having a fulcrum-pin, a slide movable upon the carrier and provided with a shoe-engaging portion, and an actuating lever movable by the operator to press the engaging portion of the slide against the shoe, said lever having a plurality of recesses any one of which may receive the fulcrum-pin.

13. In a shoe-pressing device, a carrier arranged to support a lasted shoe and having openings to hold a fulcrum-pin in different positions, a slide movable upon the carrier and provided with a shoe-engaging portion, and an actuating lever movable by the operator to press the engaging portion of the slide against the shoe, said lever having a plurality of recesses any one of which may receive the fulcrum-pin.

14. In a shoe-pressing device, a carrier arranged to support a lasted shoe and having a fulcrum-pin, a slide movable upon the carrier and provided with a shoe-engaging portion, an actuating lever movable by the operator to press the engaging portion of the slide against the shoe, said lever having a plurality of recesses any one of which may receive the fulcrum-pin, and a spring for normally retaining a chosen recess in co-operation with the pin.

15. In a shoe-pressing device, a carrier arranged to support a lasted shoe and having a unitary portion extending upwardly at one extremity and then forwardly above such supported shoe, a slide movable upon this upwardly extending portion of the carrier and provided with a shoe-engaging portion, and an actuating lever having a fulcrum mounted upon the carrier, said lever being provided with an arm for movement by the

operator and with a cam-arm for engagement with the slide.

16. In a shoe-pressing device, a carrier arranged to support a lasted shoe, pressure means movable upon the carrier and provided with a shoe-bottom-engaging portion, an actuating lever having a fulcrum mounted upon the carrier and movable by the operator to urge the engaging portion of the pressure means against the shoe-bottom, and locking means engaging the pressure means.

17. In a shoe-pressing device, a carrier arranged to support a lasted shoe, pressure means movable upon the carrier and provided with a shoe-bottom-engaging portion, an actuating lever having a fulcrum mounted upon the carrier and movable by the operator to urge the engaging portion of the pressure means against the shoe-bottom, locking means engaging the pressure means, and means movable under the influence of the lever for releasing the locking means.

18. In a shoe-pressing device, a carrier arranged to support a lasted shoe, a slide movable upon the carrier and provided with a shoe-engaging portion, an actuating lever having a fulcrum mounted upon the carrier and movable by the

operator to press the engaging portion of the slide against the shoe, a locking member engaging the pressure means, and a lock-releasing lever fulcrumed upon the carrier and movable under the influence of the actuating lever to engage 5 the locking member.

19. In a shoe-pressing device, a carrier arranged to support a lasted shoe, a slide movable upon the carrier and provided with a shoe-engaging portion, an actuating lever having a fulcrum 10 mounted upon the carrier and movable by the operator to press the engaging portion of the slide against the shoe, a locking member engaging the slide, and co-operating levers fulcrumed upon the carrier, one of said levers engaging the 15 locking member and the other being connected to the actuating lever to furnish a fulcrum therefor.

20. In a shoe-pressing device, a carrier arranged to support a lasted shoe, a slide movable 20 upon the carrier and provided with a shoe-engaging portion, a lever pivotally connected to the slide, a lever fulcrumed upon the carrier, and a link joining the two levers.

25 WILLIAM H. NUTT.
